BUS OR CAR WINDOW CONSTRUCTION

Joseph Schunk, Newark, N. J., assignor to National Lock Washer Company, Newark, N. J., a corporation of New Jersey

Application August 24, 1933, Serial No. 666,533

2 Claims. (Cl. 189—76)

This invention relates to bus or car window construction, and particularly to an improved mounting for the sash lock of a window sash, an object being to provide a construction by which the same means that are employed for connecting the side strap of the sash to the bottom rail are employed for securing the sash lock, to the end that a structure is provided which is of very simple, light and sturdy construction, having a minimum of exposed securing means, and which may be assembled and disassembled with great facility.

With the above and other objects in view an embodiment of the invention is shown in the accompanying drawing and this embodiment will be hereinafter more fully described with reference thereto, and the invention will be finally pointed out in the claims.

In the drawing:

Fig. 1 is a fragmentary inside elevation of the lower corner of the window sash, carrying the sash lock, according to the exemplary illustrated embodiment of the invention.

Fig. 2 is a vertical sectional view, taken along the line 2—2 of Fig. 1, and

Fig. 3 is a vertical sectional view, taken along the line 3—3 of Fig. 1.

Similar numerals of references will be used to denote like parts in the several figures of the drawing.

Referring to the drawing, the window sash comprises a glass 1, having a top rail (not shown), a bottom rail 2, and a pair of vertical side straps 3 connecting the top and bottom rails, only one of these straps being shown.

The bottom rail 2 is of channel shape to receive the lower edge of the glass. Upon the inner surface of each side of the channel longitudinally extending reinforcing ribs 4—4 are provided intermediate the top and bottom of the channel, and in the base of the channel there is provided a longitudinal groove 5 of corresponding width to the spacing of the ribs 4—4 for receiving the bracket tongue of the inside strap as will presently more fully appear. The edge of the glass 1 is bound with glazing tape 6 and when inserted in the channel of the rail the ribs 4—4 act as stops to limit the depth to which the glass may be engaged. The lower edge of the rail is provided with the usual sealing strip 7 of rubber, felt or the like, for engaging the sill.

The side strap 3 is of channel shape to receive the vertical edge of the glass, and at its lower end is provided with a horizontally projecting bracket tongue 8 secured at one end between the two sides

of the strap by a transverse rivet 9. This tongue is adapted to be engaged in the end of the channel of the bottom rail 2, seating in the groove 5 at its lower portion and disposed between the longitudinal ribs 4—4 at its upper portion. A pair of transverse binding screws extending through the rail and through apertures 10 and 11 in the tongue secure the latter to the rail, and, in accordance with the present invention, these screws also secure the sash lock in place, as will now appear.

The sash lock is of well known construction comprising a casing portion 12, in which the rack-engaging dog 13 is pivoted at 14 and the operating lever 15 is pivoted at 16, an extension 17 of the 15 casing being provided with a hand-lift lip or flange 18.

A circular boss 19 is formed upon the inner side of the lock casing 12 and is adapted to engage a circular recess 20 formed in the side of the 20 rail 2 in transverse alignment with the aperture 10 of the bracket tongue 8, a threaded socket 21 being provided in said boss, in axial alignment with the aperture 10 and with an aperture 22 in the inner leg of the rail and a counter-sunk 25 aperture 23 in the outer leg of the rail. A screw 24 is passed through the apertures 23, 10 and 22 and is screwed into the socket 21 to thus secure the bracket tongue 8 and sash lock case in place, the screw at the same time drawing the two sides 30 of the rail tightly together against the glass.

The extension portion 17 of the lock casing is also secured in a substantially similar manner by a binding screw comprising a tubular internally threaded part 25, engaged in a counter-sunk aperture 26 in the outer leg of the rail and extended into the aperture 11 of the bracket tongue, and an exteriorly threaded screw part 27 engaged in a counter-sunk aperture 28 in the extension and extending through an aperture 29 in the inner leg 40 of the rail into threaded engagement with the tubular part 25. It will be understood that instead of the two part binding screw 25—27 a single screw similar to the screw 24 may be employed in which case a threaded socket for receiving the screw may be provided either in the outer leg of the channel, or in the extension 17.

The sash lock may be further secured by means of an intermediate screw 30 engaged through the extension portion intermediate the pair of binding screws, but this screw 30 preferably only takes into the inner leg of the rail. It serves to retain the sash lock in place upon removal of the binding screws and separation of the side strap 3 and its bracket tongue 8 from the bottom rail 2.

I have illustrated and described a preferred and satisfactory embodiment of the invention, but it will be obvious that changes may be made therein, within the spirit and scope thereof, as defined in the appended claims.

Having thus described my invention what I claim and desire to secure by Letters Patent is:—

1. In a window construction, a glass panel, a horizontal rail of channel form receiving a horizontal edge of said glass panel, said rail having a vertical end and its channel including an upper glass receiving portion and a lower portion forming a horizontal passage below said glass panel and open at said vertical end, a removable vertical side strap of channel form receiving a vertical edge of said glass panel having a horizontal extension member permanently secured thereto, said extension member being removably engaged longitudinally within said lower portion of the channel of said rail, the vertical inner edge of said side strap engaging the vertical end of said rail, a lock casing engaged upon one side of said rail, and unitary fastening means extending between the sides of said rail and securing said lock casing exteriorly of said rail and said extension member interiorly of said rail, said fastening means adapted to draw said sides of the rail toward each other into binding relation with said extension member and with the sides of the glass panel within said rail.
2. In a window construction, a glass panel, a horizontal rail of channel form receiving a horizontal edge of said glass panel, said rail having a vertical end and its channel including an upper glass receiving portion and a lower portion forming a horizontal passage below said glass panel and open at said vertical end, a removable vertical side strap of channel form receiving a vertical edge of said glass panel having a horizontal extension member permanently secured thereto, said extension member being removably engaged longitudinally within said lower portion of the channel of said rail, the vertical inner edge of said side strap engaging the vertical end of said rail, a lock casing engaged upon one side of said rail, and unitary fastening means extending between the sides of said rail and securing said lock casing exteriorly of said rail and said extension member interiorly of said rail, said fastening means adapted to draw said sides of the rail toward each other into binding relation with said extension member and with the sides of the glass panel within said rail.

JOSEPH SCHUNK.
